SAFETY CONTROL FOR GASEOUS FUEL
BURNERS

Samuel G. Eskin and Charles K. Strobel, Pittsburgh, Pa., assignors to Robertshaw Thermostat Company, Youngwood, Pa., a corporation of Pennsylvania

Application April 10, 1943, Serial No. 482,592

15 Claims. (Cl. 158—117.1)

1

This invention relates to control systems and, more particularly, to combined safety and condition controlling means for fuel burners and the like.

In application S. N. 439,148 filed April 15, 1942, now Patent No. 2,366,774, granted January 9, 1945, there is disclosed a safety system for fuel burners employing both a flame or heat sensitive device and a current sensitive device for controlling operation of an electromagnetic fuel valve. The valve in this system was used solely for safety purposes and would function to terminate the supply of fuel to the main burner upon extinguishment of the flame to which the flame sensitive device was exposed. In this present invention it is proposed to employ the electromagnetic valve, as disclosed in the former application, both to regulate the flow of fuel to the main burner for temperature regulation and also terminate such flow in the event of flame failure. It will readily be apparent that in its broad aspects the present invention may be utilized both for condition and safety control as previously indicated.

An object of this invention is to permit utilization of the condition regulating means for safety control also.

Another object of the invention is to insure a minimum time lag in the response of the control when operation of the burner should be terminated.

Another object of the invention is to render the device substantially uniform as to operating time over a range of operating conditions.

Other objects and advantages will become apparent from the following description taken in connection with the accompanying drawing, wherein:

Fig. 1 is a schematic view of a combined safety and condition controlling apparatus for a fuel burner embodying the invention;

Fig. 2 is a schematic view of a detail in one operating position; and

Fig. 3 is a schematic view of the same detail in another operating position.

Referring more particularly to the drawing, a gaseous fuel burner 10 and an associated pilot burner 12 are shown as being supplied with fuel by a main fuel pipe 14. The fuel supply to both burners is controlled by a main valve 16 which may be manually operated. Interposed in the fuel supply line 14 between the main valve 16 and the burner 10 is an electromagnetic or solenoid gas valve 18 of any known type which may be arranged, as in this instance, to be opened when

2

sufficient energizing current is supplied to the solenoid of valve 18 and to be closed by gravity when such current is reduced below a certain minimum value. Operation of the main control valve 16 from closed to open position will permit flow of fuel from the pipe 14 to the pilot burner 12, but fuel is not supplied to the main burner 10 unless the solenoid valve 18 is also in open position.

Electric current for the operation of the apparatus is supplied by the line wires 20 connected to the primary of a transformer 22 which, in this instance, receives commercial current at the primary where a voltage variation from 105 to 125 volts can occur. In this embodiment the main valve 16 has a main switch combined therewith which is connected to one line wire 20 by wires 24 and 26. Any suitable means may be incorporated in the combined valve and switch structure to close the switch when the main valve 16 is actuated to open position. The secondary of the transformer 22 delivers the current from line wires 20 at voltages varying in accordance with the primary voltage variation above and below an average of six volts. Connected to one terminal of the transformer secondary by a wire 28 is one junction A of a parallel mesh of which a flame sensitive element 30 forms one branch and is connected at one end by wire 29 to wire 28 and at the other end by wire 31 to wire 32 at the opposite junction B of the mesh. The element 30 is positioned adjacent the pilot burner 12 exposed to the heat of the flame thereof and may be in the form of a coil of wire formed from material having normally a relatively low resistance and a positive temperature coefficient of resistance forming a ballast resistor. It will be apparent that other types of flame sensitive, heat responsive or thermal resistance elements having the required characteristics may be substituted and that it is not essential that the flame of the pilot burner 12 actually impinge on the coil.

The other terminal of the flame sensitive element 30 is connected by wires 31 and 32 with one end of another parallel mesh included in the secondary circuit, the other end of this parallel mesh being connected by a wire 34 to the other terminal of the secondary of the transformer 22. One branch of this parallel mesh comprises a resistance element 36 which will be hereinafter designated as a valve control resistor. This resistor 36 is preferably in the form of a coil of wire of material having normally a relatively low resistance and a positive temperature coefficient of resistance forming a ballast resistor, although, as

will appear hereinafter, a constant resistor could be employed. The resistor 36 is not, however, exposed to the heat of any flame but is adapted to become heated upon passage of electric current therethrough and will change its resistance in accordance with changes of temperature caused by changes in the value of current flowing through it.

The other branch of the parallel mesh comprises a constant resistance element 38 forming a pick-up resistor for the solenoid valve, and a control switch connected in series circuit therewith. The control switch may take the form of a thermostat composed of a bimetal arm 40 carrying on one end thereof a pair of contacts 41, 43 disposed one on each side and which upon warping of the arm will engage alternately with contacts 42 and 46, designated hot contact and cold contact respectively, and spaced one from the other. The control switch may be placed in the space to be heated by the main burner 10 and the arm 40 be subjected to the temperature variations therein forming a space thermostat of special form. To this end, the cold contact 46 is preferably carried upon a second bimetal arm 44 which is adapted to warp upon passage of electric current therethrough so that only the hot contact 42 can be considered as a relatively fixed contact for the thermostatic switch. A limit stop 48 is interposed between the bimetal arms 40 and 44 in position to be engaged by the arm 40 to restrain movement thereof toward the arm 44 for a purpose which will be apparent hereinafter.

The hot contact 42 is connected by a wire 50 to one end of a constant resistance element 52, the other end of which is connected by a wire 51 to wire 28 at junction A of the parallel mesh. Another branch of this mesh includes a cut-out 58 which is thermally sensitive and may be of the slow acting bimetallic snap switch type. One terminal of the cut-out 58 is connected by a wire 53 to the wire 28 at junction A and the other terminal is connected by wire 54 to one terminal of the solenoid valve 18. The other terminal of the solenoid valve 18 is connected by a wire 56 to the wire 32 at the junction B, thus placing the flame sensitive element 39 in parallel circuit with the cut-out 58 and solenoid valve 18.

In the operation of the apparatus the closing of the main switch of valve 16 is effective upon manual opening of this valve, as described, and permits fuel to flow to the pilot burner 12. As the solenoid valve 18 remains closed, no fuel can flow to the main burner 10 at this time. The circuit thus established may be traced from the line wire 20 to wire 24, electric switch of main valve 16 and wire 26 to the primary of the transformer 22, from the secondary of the transformer by wire 28 to wire 53, cut-out 58, wire 54, to one terminal of solenoid valve 18, wire 56 to wire 32, valve control resistor 36 and wire 34 to the other side of the transformer secondary. Current also flows in the shunt established by the flame sensitive element 39 which is connected by wires 29 and 31 around the coil of the solenoid valve 18 causing the element 39 to become heated to some extent. During this starting operation the control thermostat is usually in cold-contact position so that pick-up resistor 38 is connected in parallel circuit with the valve control resistor 36. The current values in the circuit are adjusted so that when these circuit conditions exist and the flame sensitive element 39 remains unheated by the pilot burner flame, there is insufficient current flowing

to the coil of the solenoid valve 18 to actuate this valve to open position.

The fuel issuing from the pilot burner 12 may be ignited by a match and the relatively small heating effect of the current on the flame sensitive element 39 is amplified by the much greater heating effect of the pilot burner which will then occur. Assuming that the control thermostat is in the cold contact position with the contact 46 engaged by related contact on arm 40, then the circuit will be as previously described, that is, the parallel mesh of pick-up resistor 38 and valve control resistor 36, the parallel mesh of solenoid valve 18 with its cut-out 58 and flame sensitive element 39, all in series with the transformer secondary. Upon heating of the flame sensitive resistor 39 by the pilot flame in this starting or cold contact position, the shunting of the valve control resistor 36 by the pick-up resistor 38 and cold contact 46 causes sufficient current to flow through the solenoid valve 18 to actuate this valve to open position. As in the case of application Serial No. 439,148 previously referred to, this effect is produced by a relatively large increase of resistance with increase of temperature of the flame sensitive resistor 39. However, if the flame sensitive resistor 39 is not heated by the pilot flame there is insufficient current impressed upon the coil of the solenoid valve 18 to effect actuation of the valve to open position as previously described therein.

Operation of the main burner 10 will serve to increase the temperature ambient to the thermostat causing movement of the bimetal arm 40 toward the hot contact 42. It may be assumed for the purpose of this description that the bimetal arm 40 now moves to a neutral position engaging neither the cold contact 46 nor the hot contact 42. A circuit is then established from the valve control resistor 36, the parallel mesh of solenoid valve 18 with its cut-out 58 and flame sensitive element 39 all in series with the transformer secondary. In this circuit the resistor 38 and resistor 52 are disconnected as will be apparent and the current through the solenoid valve 18 is consequently reduced by removal of resistor 38 from parallel relation with the valve control resistor 36. However, when the thermostat moves as described from the cold contact to neutral position the current value impressed on solenoid valve 18 is not reduced below the minimum value required to hold the valve in its open or operating position, but the circuit constants are adjusted at the lowest line voltage which may be 105 volts at the primary so that the normal, steady operating current is slightly above the minimum value. The resistance of the parallel circuit in operating condition is increased sufficiently by the higher resistance value of the flame sensitive element 39 when heated to permit sufficient current to the solenoid valve to maintain it in the open position.

After the main burner 10 has been operating for some time the bimetal arm 40 may move to the hot contact position due to the thermostat becoming satisfied, whereupon a circuit arrangement is established from the transformer secondary and the valve control resistor 36 in series with the three-branch parallel mesh of flame sensitive resistor 39, solenoid valve 18 and cut-out 58, and constant resistor 52 with the hot contact 42. The constant resistor 52 which acts as an adjusting resistor for the solenoid valve 18 is of such a value as to shunt sufficient current from the sole-

noid valve 18 to cause this valve to move to closed position.

When the thermostat moves from the hot contact 42 to the neutral position the solenoid valve 18 remains closed until the bimetal arm warps to close the cold contact 46. In such event the cycle is repeated due to the flame sensitive element 30 being heated by the pilot burner. In case the flame sensitive element 30 becomes open circuited, sufficient current flows through the cut-out 58 to cause it to operate to close the valve, providing the thermostat is in either the cold contact position or neutral position. If, however, the thermostat is in the hot contact position, the solenoid valve 18 is closed due to the shunting action of the resistor 52.

The foregoing sequence of operation continues during the normal running condition of the burner to control a condition caused by operation of the burner. The operation of the safety device will now be described.

If the flame of the pilot burner 12 becomes extinguished for any reason when the bimetal arm 40 is in the hot contact position, or in the neutral position upon warping from the hot contact position, then the solenoid valve 18 is already closed at the time of the flame failure. If, however, the bimetal arm 40 is in the neutral position upon warping from the cold contact position, the solenoid valve 18 is open. The flame sensitive element 30 will cool in the absence of pilot burner flame and its resistance will decrease causing a corresponding decrease in current value to the solenoid valve 18 which then closes. Such closing of the solenoid valve occurs in a relatively short time due to the combined action of the flame sensitive resistor 30 and the valve control resistor 36. As previously described, the current impressed upon the solenoid valve 18 in the neutral position of the thermostat is only slightly above the minimum value required to hold the valve in its open or operating position. Thus, by making the valve control resistor 36 sensitive to current changes the decrease in voltage drop across the coil of the solenoid valve will be accelerated whenever an increase of resistance of the valve control resistor occurs upon cooling of the flame sensitive resistor 30 and consequent increase in current through the valve control resistor. The resulting temperature increase in valve control resistor 36 causes increase in voltage drop across this resistor and the rapid decrease in voltage drop across solenoid valve 18.

In order to make the adjustment of the circuit constants less critical and the shut-off times of the solenoid valve comparatively short, the cold contact 46 of the thermostat is mounted on the bimetal arm 44. Thus, upon closure of the cold contact the bimetal arm 44 will warp, after the circuit has been established, from the position shown in Fig. 2 to that shown in Fig. 3. Even if the thermostat arm 40 remains in cold contact position, the contacts separate and rejoin several times as the arm 44 heats and cools upon automatic making and breaking of the circuit. Thus, the bimetal arm 44 serves to open the cold contact 46 independently of the controlled temperature when the cold contact remains closed for a given length of time. The normal operation of the system is not affected by this action of the arm 44 as once the solenoid valve is actuated to open position it remains open until the hot contact is made. Due to the provision of the stop 48, the thermostat arm 40 is restrained from following movement of the arm 44 to the left as

viewed in Fig. 3, and a separation of the cold contact 46 from arm 40 can occur as soon as the arm 44 becomes heated by passage of current therethrough. The separation of the cold contact thus has the same effect as movement of the arm 40 to neutral position and the valve closing time is generally short. It will be apparent that a heater coil could be used in place of conducting current directly to the arm 44 and such variation is within the scope of this invention.

It will be understood that a constant resistor could be used in place of the current sensitive resistor as the valve control. The system would then operate over a narrower range of voltages and the valve closing times would be increased. However, the system would not in such case be quite as sensitive as the preferred form to rapid voltage variations, and the advantages of reduced valve closing times and an extension of the primary voltage range over which the system will operate are believed superior. Considerable flexibility of circuit arrangement results as the value of the respective resistances can be varied to suit different operating conditions. The single solenoid valve functions as condition and safety control in the arrangement described and it will be apparent that various changes may be made in the form and arrangement of parts within the scope of the appended claims.

We claim:

1. A control system for fuel burners having main and pilot burners comprising in combination, electrically operable control means movable between positions for controlling the main burner, a controller in circuit with said means and responsive to changes in a condition caused by operation of the main burner, a ballast resistor exposed to the heat of the pilot burner flame and electrically connected to said control means for varying the current value supplied thereto upon variations in the resistivity of said resistor due to the presence or absence of said flame, and a plurality of resistance circuits adapted to be established alternately by operation of said controller and including said control means and said ballast resistor, said resistance circuits having different resistance values for varying the current values to said control means, said means being movable to one position upon establishment of one said resistance circuit for impressing a predetermined current value thereon and maintained in said position upon establishment of another said circuit for impressing a different current value thereon, said resistor being adapted by said variations in resistivity thereof for cooperating with said resistance circuits to determine whether said control means is moved and maintained in said position.

2. A control system for fuel burners having main and pilot burners comprising in combination, electrically operable control means movable between positions for controlling the main burner, a control switch having a pair of contacts adapted to be opened and closed for controlling current supply to said means in response to changes in a condition caused by operation of the main burner, a ballast resistor exposed to heat of the pilot burner flame and electrically connected to said control means for varying the current value supplied thereto upon variations in the resistivity of said resistor due to the presence or absence of said flame, a resistance circuit adapted to be established upon closure of said contacts and including said control means and said ballast resistor for adjusting the cur-

rent value to said control means and causing movement thereof to one position, and a second resistance circuit established upon opening of said contacts and including said control means and said ballast resistor, said second resistance circuit having a resistance value different from the first said resistance circuit for changing the current value to said control means, the last said current value being insufficient to cause said movement but sufficient to maintain said position, said resistor being adapted by said variations in resistivity thereof for cooperating with both said resistance circuits to determine whether said control means is moved and maintained in said position.

3. A control system for fuel burners having main and pilot burners comprising in combination, electrically operable control means movable between positions for controlling the main burner, a control switch having a pair of contacts adapted to be opened and closed for controlling current supply to said control means in response to changes in a condition caused by operation of the main burner, means for rendering one of said contacts responsive to current flow acting to open said contacts when closed, a ballast resistor exposed to heat of the pilot burner flame and electrically connected to said control means for varying the current value supplied thereto upon variations in the resistivity of said resistor due to the presence or absence of said flame, a pair of resistance circuits adapted to be established alternately by closure and opening of said contacts and including said control means and said ballast resistor, said resistance circuits having different resistance values for adjusting the current value to said control means, said control means having sufficient current value impressed thereon when said contacts are closed to cause movement thereof to one position and having only sufficient current value impressed thereon when said contacts are open to maintain said one position, said resistor being adapted by said variations in resistivity thereof for cooperating with both said resistance circuits to determine whether said control means is moved and maintained in said position.

4. A control system for fuel burners having main and pilot burners comprising in combination, electrically operable control means movable between positions for controlling the main burner, a control switch having a pair of contacts adapted to be opened and closed for controlling current supply to said means in response to changes in a condition caused by operation of the main burner, means for rendering one of said contacts responsive to current flow acting to open said contacts when closed, a ballast resistor connected in parallel circuit with said control means and exposed to heat of the pilot burner flame for varying the current value supplied thereto upon variations in the resistivity of said resistor due to the presence or absence of said flame, and a pair of resistances in mutual parallel relation and jointly connected in series circuit with said control means and said ballast resistor, one of said resistances being connected in said series circuit by operation of said contacts and being cooperable with the other said resistance for adjusting the current value to said control means when said contacts are closed whereby said control means is caused to move to one of said positions upon the variation in resistivity of said ballast resistor due to the presence of said flame.

5. A control system for fuel burners having

main and pilot burners comprising in combination, electrically operable control means movable between positions for controlling the main burner, a control switch having hot and cold contacts

5 for controlling current supply to said means in response to changes in a condition caused by operation of the main burner, said switch being movable to a neutral position for establishing circuit conditions different from those established in said hot and cold contact positions, a ballast resistor exposed to heat of the pilot burner flame and electrically connected to said control means for varying the current value supplied thereto upon variations in the resistivity of said resistor 10 due to the presence or absence of said flame, a resistance circuit adapted to be established upon closure of said cold contacts and including said control means and said ballast resistor for adjusting the current value to said control means and causing movement thereof to one position if the resistivity of said resistor has varied as aforesaid due to the presence of a flame, means for rendering said cold contacts responsive to current flow in said circuit to cause movement thereof to said neutral position, a second resistance circuit including said control means and said ballast resistor having a greater resistance value than the first said circuit and established in said neutral position for causing a reduction in the current value to said control means 15 to an amount sufficient to maintain said one position thereof but insufficient to cause said movement of said control means, said ballast resistor being effective by said variations in resistivity 20 thereof under both said circuit conditions to determine whether said control means is moved and maintained in said position, and means establishing a third resistance circuit upon closure of said hot contacts and including said control means, said ballast resistor and said second resistance circuit, said third resistance circuit having a greater resistance value than said second resistance circuit for reducing the current value to said control means and causing movement thereof from said one position to initial position 25 irrespective of the heated or unheated condition of said ballast resistor.

6. A control system for fuel burners having main and pilot burners comprising in combination, electrically operable control means movable between positions for controlling the main burner, a control switch having hot and cold contacts for controlling current supply to said means in response to changes in a condition caused by operation of the main burner, said switch being movable to a neutral position for establishing circuit conditions different from those established in said hot and cold contact positions, a ballast resistor connected in parallel circuit with said control means and exposed to heat of the pilot burner flame and electrically connected to said control means for varying the current value supplied thereto upon variations in the resistivity of said resistor due to the presence or absence of said flame, a pair of resistances in mutual parallel relation and adapted to be jointly connected in series circuit with said control means and said ballast resistor, one of said resistances being connected in said series circuit by closure of said cold contacts and being thereby cooperable with the other said resistance for adjusting the current value to said control means to cause movement thereof to one of said positions upon the variation in resistivity of said ballast resistor due 70 to the presence of said flame as aforesaid, and a

third resistance adapted to be connected in parallel circuit with said control means and said ballast resistor and in series circuit with said other resistance upon closure of said hot contacts for adjusting the current value to said control means and causing movement thereof from said one position to initial position irrespective of the heated or unheated condition of said ballast resistor.

7. In a combined temperature and safety control for fuel burners, the combination with electrically operated fuel control means and a plurality of electrical circuits for said means having different resistance values, of a control switch operable for alternatively establishing said circuits and thereby varying the current value to said means, said switch comprising a thermally responsive element movable in response to changes in ambient temperature caused by operation of a burner, a second thermally responsive element movable in response to passage of electric current therethrough, switching means operable by movement of said first element upon one ambient temperature condition to establish one of said circuits and cause variation in the current value to said control means, said second element being moved upon said operation of said switching means to discontinue said passage of current therethrough and cause return of said second element to initial position to establish a second one of said circuits and another variation in the current value to said control means, and second switching means operable by movement of said first element upon another ambient temperature condition to establish a third one of said circuits and cause a further variation in the current value to said control means.

8. The combination with a fuel burner system comprising a main fuel burner, a pilot burner, electrically operable control means, a controller, and an electrical circuit including said controller and control means for controlling said main burner, of a first resistor exposed to the heat of the pilot burner flame for varying the current value supplied thereto upon variations in the resistivity of said resistor due to the presence or absence of said flame, a pair of resistors one of which changes its resistivity upon a change in temperature of said one resistor due to the flow of current in said circuit, means associated with said controller for connecting said pair of resistors in said circuit in mutual parallel relation and in series circuit with said control means and first resistor in mutual parallel relation thereby causing sufficient current to be impressed on said control means to actuate it to one controlling position when said first resistor is heated, and means associated with said controller and responsive to current flow in said circuit for electrically disconnecting the other one of said pair of resistors from said circuit when said control means is in said one controlling position, said first resistor and said one resistor having a combined resistance value such as to cause only sufficient current to be impressed upon said control means to maintain it in said position but insufficient to effect actuation thereof.

9. The combination with a fuel burner system comprising a main fuel burner, a pilot burner, electrically operable control means, a controller, and an electrical circuit including said controller and control means for controlling said main burner, of a first resistor exposed to the heat of the pilot burner flame for varying the current value supplied thereto upon variations in the resistivity

of said resistor due to the presence or absence of said flame, a pair of resistors one of which changes its resistivity upon a change in temperature of said one resistor due to the flow of current in said circuit, a bimetal switch arm in said controller movable in one direction when said main burner is not operating for connecting said pair of resistors in said circuit in mutual parallel relation and in series circuit with said control means and first resistor in mutual parallel relation thereby causing sufficient current to be impressed on said control means to actuate it to a position for supplying fuel to said main burner when said first resistor is heated, a second bimetal switch arm in said controller movable in one direction in response to current flow in said circuit for electrically disconnecting the other one of said pair of resistors from said circuit, said first resistor and said one resistor having a combined resistance value such as to cause a reduction in the current value impressed upon said control means to an amount sufficient only to maintain said position but insufficient to effect actuation thereof, and means cooperable with said first bimetal arm upon movement thereof in another direction for introducing additional resistance in parallel circuit with said control means while the current value thereto is so reduced to render said current insufficient to maintain said position and cause discontinuance of fuel supply to the main burner.

10. A control system for fuel burners having main and pilot burners, comprising an electrically operable device for controlling supply of fuel to the main burner, said fuel supply being contingent upon current of a predetermined minimum value being supplied to said device, a source of current supply for said device and being of at least said minimum value, a ballast resistor electrically connected to said device and exposed to the heat of a flame at the pilot burner for varying the current value to said device according to variations in the resistance of said ballast resistor due to the presence or absence of said flame, a resistance element in circuit with said device and ballast resistor and cooperable with said ballast resistor to cause said current value to fall below said minimum upon the variation in resistance of said ballast resistor due to the extinguishment of the flame at the pilot burner, a controller responsive to changes in a condition caused by operation of the main burner and means controlled by said controller for introducing additional resistance into said circuit and being cooperable with said resistance element to cause said current value to fall below said minimum irrespective of the heated condition of said ballast resistor.

11. A control system for fuel burners having main and pilot burners, comprising an electrically operable device for controlling supply of fuel to the main burner, said fuel supply being contingent upon current of a predetermined minimum value being supplied to said device, a source of current supply for said device and being of at least said minimum value, a ballast resistor electrically connected to said source in shunt with said device and exposed to the heat of a flame at the pilot burner for varying the current value to said device according to variations in the resistance of said ballast resistor due to the presence or absence of said flame, a resistance element cooperable with said ballast resistor and connected in series circuit with said resistor and device to cause said current value to fall below said minimum upon the variation in resistance

of said ballast resistor due to the extinguishment of the flame at the pilot burner, a controller responsive to changes in a condition caused by operation of the main burner, and means controlled by said controller for introducing additional resistance in shunt with said device and being cooperable with said resistance element to cause said current value to fall below said minimum irrespective of the heated condition of said ballast resistor.

12. A control system for fuel burners having main and pilot burners, comprising electrically operable means movable between positions for controlling the fuel supply to the main burner, a ballast resistor having a preselected temperature coefficient of resistance located to be heated by the pilot burner and electrically connected to said means, a control switch for said means including a plurality of pairs of contacts adapted to be alternatively closed in response to changes in a condition caused by operation of the main burner, separate circuits for said means established respectively by closure of said contact pairs and having different resistance values, one of said circuits having a resistance value in the heated condition of said ballast resistor such that the current value to said means is sufficient to cause movement thereof to fuel supply position and another said circuit having a resistance value such that the current value is insufficient to maintain said means in said fuel supply position, and a circuit for said means established in the open position of all of said contact pairs and having a resistance value intermediate those of said separate circuits for rendering the current value ineffective to cause said means to change the position to which it has been moved by establishment of said one or another of said separate circuits, said ballast resistor being effective upon extinguishment of said flame for increasing the resistance value of the last said circuit and thereby reducing the current value to said means sufficiently to cause movement thereof from said fuel supply position.

13. A control system for fuel burners having main and pilot burners, comprising electrically operable means movable between positions for controlling the supply of fuel to the main burner, a ballast resistor electrically connected to said means and responsive to the presence or absence of a flame at the pilot burner for varying the current value supplied to said means, a thermostatic control switch for said means including two pairs of contacts adapted to be alternatively closed in response to changes in a temperature condition caused by operation of the main burner, a circuit for said means established upon closure of one of said contact pairs on a drop in said temperature and having a resistance value such that the current value to said means is sufficient to cause movement thereof to fuel supply position, a second circuit for said means established in the open position of said two contact pairs on a rise in said temperature and having a resistance value greater than that of the first said circuit to reduce the current value to said means but insufficiently to cause movement from said fuel supply position, a third circuit for said means established upon closure of the other of said

contact pairs on a further rise in said temperature and having sufficiently greater resistance than said second circuit to render the current value to said means insufficient to maintain said means in fuel supply position in the heated condition of said ballast resistor, and thermally responsive means operable to cause opening of said one contact pair to establish said second circuit irrespective of said temperature condition.

- 10 14. In a control system for fuel burners, electrically operable fuel control means arranged for fuel supply to a burner when said means is placed in energized condition and for preventing said fuel supply when placed in effectively deenergized condition, a control switch for said means including a plurality of contact pairs adapted to be alternatively closed in response to changes in a condition caused by operation of the burner, said switch having an open position of all of said 15 contact pairs, a circuit for said fuel control means initially established in the open position of said switch, means responsive to closure of one of said contact pairs for reducing the total resistance value of said circuit sufficiently to cause said 20 fuel control means to be placed in said energized condition, and means responsive to closure of another one of said contact pairs for increasing the total resistance value of said circuit sufficiently to cause said fuel control means to be placed in said effectively deenergized condition, said circuit as initially established having a resistance value such that said control means is maintained in the condition in which it has been placed by a preceding closure of either said one or the other of 25 said contact pairs.
- 15 15. In a control system for fuel burners, electrically operable fuel control means arranged for fuel supply to a burner when said means is placed in energized condition and for preventing said fuel supply when placed in effectively deenergized condition, a control switch for said means including a plurality of contact pairs adapted to be alternatively closed in response to changes in a condition caused by operation of the burner, 30 said switch having an open position of all of said contact pairs, a circuit for said fuel control means initially established in the open position of said switch and including a resistor, means responsive to closure of one of said contact pairs for introducing resistance means in parallel circuit with said resistor for reducing the total resistance value of said circuit sufficiently to cause said fuel control means to be placed in said energized condition, and means responsive to closure of another one of said contact pairs for introducing another 35 resistance means in parallel circuit with said fuel control means for increasing the total resistance value of said circuit sufficiently to cause said fuel control means to be placed in said effectively deenergized condition, said circuit as initially established having a resistance value without either of said resistance means such that said control means is maintained in the condition in which it has been placed by a preceding closure of either said one or the other of said contact pairs.
